UNITED STATES PATENT OFFICE

151,786

DESIGN FOR A RADIO RECEIVER CABINET

Wallace Schier, Forest Hills, and David L. Doggett, Mount Kisco, N. Y., assignors to Federal Telephone and Radio Corporation, New York, N. Y., a corporation of Delaware

Application January 11, 1947, Serial No. 136,079

Term of patent 3½ years

(Cl. D56—4)

To all whom it may concern:

Be it known that we, Wallace Schier and David L. Doggett, citizens of the United States, residing at 150 Greenway Terrace, Forest Hills, Long Island, New York, and Millwood Road, Mount Kisco, New York, respectively, have invented a new, original, and ornamental Design for a Radio Receiver Cabinet, of which the following is a specification, reference being had to the accompanying drawing, forming part thereof.

Figure 1 is a view in perspective of the radio receiver cabinet, showing the front panel in closed position;

Figure 2 is a view in perspective of the cabinet at a slightly different angle with the front panel pivoted to open position; and

Figure 3 is a view in elevation of the left-hand side of Figure 2.

The characteristic features of our design reside in the portions shown by means of full lines in the drawing.

We claim:
The ornamental design for a radio receiver cabinet, substantially as shown and described.

WALLACE SCHIER.
DAVID L. DOGGETT.
